UNITED STATES PATENT OFFICE.

FRANK GRAY, OF ATLANTIC CITY, NEW JERSEY.

PROPELLING MECHANISM FOR VESSELS.

SPECIFICATION forming part of Letters Patent No. 605,782, dated June 14, 1898.

Application filed May 14, 1897. Serial No. 636,581. (No model.)

To all whom it may concern:

Be it known that I, FRANK GRAY, of Atlantic City, in the county of Atlantic and State of New Jersey, have invented certain new and useful Improvements in Propelling Mechanism for Steam Vessels; and I do hereby declare the following to be a full, clear, and exact description of the invention, such as will enable others skilled in the art to which it appertains to make and use the same.

My invention relates to propelling mechanism for vessels of that type wherein a water-cylinder containing a ram operated by suitable mechanism is employed for displacing the water at the rear of the vessel, and thereby driving the same forward.

The object of my invention is to provide improved mechanism of this type; and it consists in disposing within the hull of the vessel a water-cylinder opening through the stern of the vessel and a steam-cylinder of relatively smaller diameter and provided with a plunger-rod, to which the two pistons or plungers are connected, and also provided with mechanism for regulating the speed of the plungers and cushioning the same on their return strokes, as will be hereinafter more fully described, and specifically set forth in the appended claim.

In the accompanying drawings, illustrating the invention, Figure 1 is a vertical longitudinal section of my invention applied in the stern of a vessel, the latter being represented by broken lines. Fig. 2 is a view looking toward the stern of the vessel, and Fig. 3 is an enlarged detail view of the steam-chest and parts.

Like numerals designate corresponding parts throughout the several figures of the drawings.

Referring to the drawings, the numeral 1 designates a vessel-hull, and 2 a water-cylinder placed within the vessel and having its outer end open and exposed at an opening 3 in the stern of the vessel. The inner end of the water-cylinder is closed, and the open outer end thereof does not project beyond the line of the vessel, and hence injury thereto is prevented. A steam-cylinder 4 is arranged in line with the water-cylinder, but is of relatively smaller diameter.

5 designates a plunger-rod operating in

stuffing-boxes 6 in the adjacent heads of the two cylinders, and provided at one end, within the water-cylinder, with a ram or plunger 55 8 and at the other end, within the steam-cylinder, with a steam-plunger 9. The steam-cylinder is provided with a steam-chest 10, having a steam-supply pipe 11 leading from the boiler, and is in communication with the steam-cylinder by means of a steam-supply port 12, controlled by a slide-valve 13, with which a valve-rod 14 is connected, said rod being supported at its outer end in guides 15, secured to the closed head of the water-cylinder. 65 The steam-cylinder is also provided with a steam-exhaust port 17, controlled by a slide-valve 18, with which a valve-rod 19 is connected, said rod working in guides 20 on the water-cylinder. This latter valve is inclosed 70 within a steam-exhaust chest 21, from which an exhaust-pipe 22 extends to the condenser of the vessel. Suitable mechanism is provided for automatically opening and closing the said valves and controlling the admission 75 and exhaust of steam to the steam-cylinder. To this end the plunger-rod is provided with a tappet-rod 23, projecting toward the valve-rod of the steam-supply valve, which is adapted to engage tappet-blocks 24 25 on the said 80 valve-rod and slide the rod to actuate the valve. The valve-rod 19 of the exhaust-valve is provided with tappet-blocks 26 27, with which a tappet-rod 28, projecting from the plunger-rod, is adapted to engage to open 85 and close said valve and regulate the exhaust-steam from the steam-cylinder.

The water-cylinder is provided with an air-supply pipe 29, leading to an air tank or chamber 30, the object of which is to supply the 90 closed end of the cylinder with air to serve as a cushion upon the return stroke of the ram or plunger. The water-cylinder is also provided with a water-supply pipe 31, projecting through the hull of the vessel into the water 95 and provided with a controlling-cock 32 to regulate the passage of water therethrough. This water-supply pipe is provided to supply water to the closed end of the cylinder to serve as a cushion to regulate the speed of the plunger when it is desired to run the vessel at a 100 very low speed. It is apparent that no matter what amount of steam is supplied to the steam-cylinder to cause the plungers to make

their outward stroke the pressure of the water on the water-cylinder would be so great as to cause it to make its return stroke with great velocity, thereby rendering the propelling mechanism liable to damage. By means of the air-supply tank or chamber on the water-supply pipe leading to the water it will be seen that the vacuum caused by the outstroke of the piston will cause an inrush of water and air which will retard the piston on its return stroke and regulate the speed thereof, the quantity of water passing through the supply-pipe being regulated by the controlling-cock.

15 Having thus described my invention, what I claim as new, and desire to secure by Letters Patent, is—

In a propelling mechanism for vessels, the combination of a cylinder closed at its inner end and open at its outer end, said end being exposed in an opening at the stern of the vessel, a steam-cylinder arranged in line with the water-cylinder, a piston-rod movable in axial line with said cylinders through stuff-

ing-boxes in the adjacent heads thereof, a 25 plunger upon the outer end of said movable rod within the water-cylinder, a piston on the other end movable within the steam-cylinder, a steam-chest upon one end of the steam-cylinder having connection with the boiler, a 30 sliding valve in said chest, a sliding valve controlling an exhaust-port on the opposite side of said cylinder and having connection with the condenser, connecting devices between the piston-rod and the valve-rods intermediate the two cylinders for automatically opening and closing said valves, and air and water supply pipes connected with the water-cylinder at the inner end thereof, all substantially as shown and described.

35 In testimony whereof I have signed this specification in the presence of two subscribing witnesses.

FRANK GRAY.
